UNITED STATES PATENT OFFICE

FREDERICK STANTON, OF GRAND MERE, QUEBEC, CANADA

CLOSER FOR COLLAPSIBLE TUBES

Application filed February 28, 1931. Serial No. 519,125.

- This invention relates to collapsible tubes for tooth paste, shaving cream and the like, and has for one of its objects to provide a novel closure for a tube of this character which shall embody a cap which cannot be removed from the tube and cannot therefore become lost, and which will prevent waste of the contents of the tube and keep the contents clean and prevent the access of air thereto.
- 10 The invention has for a further object to provide a closure of the character stated which shall be simple and capable of being applied to a tube without requiring any expensive changes in the method of manufacturing the tube, and which may be made of metal or any other suitable material.
- With the foregoing and other objects in view, the nature of which will appear as the description proceeds, the invention consists 20 in the construction, combination and arrangement of parts hereinafter fully described and claimed, and illustrated in the accompanying drawings, wherein:—
- Figure 1 is a view in side elevation of the upper portion of a collapsible tube equipped 25 with a closure constructed in accordance with my invention, the closure being shown in opened position.
- Figure 2 is a sectional view taken on the plane indicated by the line 2—2 of Figure 1.
- Figure 3 is a sectional view taken on the plane indicated by the line 3—3 of Figure 1, and
- Figure 4 is a view similar to Figure 3 with the closure in tube sealing position.
- Referring in detail to the drawings, 1 designates the body, 2 the breast and 3 the neck of a collapsible tube for tooth paste, shaving cream and the like. In accordance 10 with my invention, the neck 3 is closed at its upper end and is provided in its side wall with a discharge opening 4. The upper end of the neck 3 is closed by a plug 5 which is screw-threadedly engaged in the neck and 15 which is provided at its upper end with an annular flange 6 which extends radially beyond the wall of the neck. A sleeve 7 is rotatably mounted upon the neck 3 between the upper end of the breast 2 of the tube and the flange 6 of the plug 5, the breast and flange serving to hold the sleeve against any axial movement on the neck. The sleeve 7 is provided with an opening 8, and it is adapted to be turned on the neck 3 to move its opening into and out of registration with the opening 4 of the neck. The sleeve opening 8 is larger than the neck opening 4 in order to permit the free passage of the contents of the tube through these openings when they are in registration. The sleeve is provided at its upper end with an annular flange 9 which extends radially beyond the flange 6 of the plug 5, and which provides means through the medium of which the sleeve may be turned to move its opening 8 into and out of registration with the opening 4 of the neck 3.
- To adapt a collapsible tube for the application thereto of my improved closure, it is only necessary to provide the neck 3 of the tube with the radial discharge opening 4, and screw thread the inner wall of the upper portion of the neck. After the sleeve 7 has been applied to the neck 3, the plug 5 is applied to the neck in order to secure the sleeve against removal from the neck and thus prevent the loss of the same. The sleeve 7 has a snug fit on the neck 3, and in view thereof the contents of the tube will be protected from the air and will be kept in a clean state. When it is desired to withdraw some of the tooth paste, shaving cream or the like from the tube, the sleeve 7 is turned through the medium of the flange 9 in order to register its opening 8 with the neck opening 4, and after the desired quantity has been withdrawn from the tube the sleeve is turned to move its opening out of registration with the neck opening. As the closure consists merely of the plug 5 and sleeve 7, it is of very simple construction, may be manufactured at a comparatively low cost, and may be readily applied to the neck 3 of the tube. As the sleeve 7 has a snug fit on the neck 3, it will be held against accidental turning on the neck.
- While I have described the principle of the invention, together with the structure which I now consider the preferred embodiment thereof, it is to be understood that the struc-

ture shown is merely illustrative and that such changes may be made, when desired, as fall within the scope of the invention as claimed.

5 What is claimed is:—

- A collapsible tube having a neck provided with a radial discharge opening, a sleeve mounted on the neck and provided with a radial opening and provided at its upper end 10 with an outwardly directed annular flange, the sleeve being adapted to be turned through the medium of its flange to move its opening into and out of registration with the neck opening, and a plug screw-threadedly 15 engaged in the upper end of the neck and provided with an annular flange extending radially beyond the neck and contacting with the upper end of the sleeve to maintain the sleeve on the neck, the flange of the sleeve 20 projecting radially beyond the flange of the plug to permit it to be readily grasped.

In testimony whereof I hereunto affix my signature.

FREDERICK STANTON.
